UNITED STATES PATENT OFFICE.

MICHAEL J. KULLA, OF LORAIN, OHIO.

LUBRICATOR-VALVE MECHANISM.

1,087,023.

Specification of Letters Patent. Patented Feb. 10, 1914.

Application filed October 25, 1912. Serial No. 727,756.

To all whom it may concern:

Be it known that I, MICHAEL J. KULLA, a citizen of the United States, residing at Lorain, in the county of Lorain and State of Ohio, have invented certain new and useful Improvements in Lubricator-Valve Mechanism, of which the following is a specification.

This invention relates to improvements in valves, and particularly to valves of the automatic check type.

The invention comprises, generically, a casing, a sliding seat therein, and a flap valve carried by the seat and movably connected therewith to shift to and from a seat-engaging position relative to movements of the sliding seat.

The invention further comprises, more specifically, the combination, with a casing, of a sliding seat therein recessed to accommodate a flap valve, and a flap valve movably engaging the seat, the face of the seat being concaved from its outer portions toward the point of contact of the flap valve when seated.

The invention also comprises the combination, with a container and a casing extending therefrom, of a valve seat slidably mounted in the casing, a tubular extension projecting from the valve seat into the container, said extension being formed with an opening adapted when the seat is shifted toward the container to move into position for receiving fluid from the container, and a flap valve movably connected to the seat in position for closing communication through said tubular extension.

The invention still further comprises certain other novel constructions, combinations and arrangements of parts, as will be hereinafter specified and claimed.

In the accompanying drawing: Figure 1 is a longitudinal vertical central section through a valve mechanism embodying the features of the present invention. Fig. 2 is a transverse section taken on the plane indicated by line 2—2 of Fig. 1 and looking upwardly. Fig. 3 is a longitudinal vertical section taken on the plane indicated by line 3—3 of Fig. 1 and looking in the direction indicated by the arrow.

Referring to the drawing by numerals, 1 indicates the container adapted to contain fluid to be distributed and controlled, as for

instance lubricating oil for the cylinder of 55 an internal combustion engine. Pendent from the cover of container 1 is a tube 2 which extends within the container to a point adjacent the bottom thereof, and threaded within the tube 2 is an adjusting 60 bolt 3 having its inner end extending sufficiently within the tube 2 to be adapted to be moved, by the threading of the bolt, beyond the inner or lower end of the tube 2, the inner end portion of the bolt 3 being 65 formed with a bore 4 for accommodating the tubular extension 5 of a valve seat 6, the upper end portion of the tubular extension 5 being dimensioned to slidably fit within the bore 4. The seat 6 is slidably mounted 70 within a casing 7 and snugly fits the same, the said casing being fixed to and pendent from the bottom of the container 1, and a bushing or other suitable annular filler 8 is arranged within the upper end of the casing 75 7 and has its bore of a size to snugly accommodate and permit reciprocation of the tubular extension 5, the lower end of the bushing 8 forming an annular shoulder adapted to be engaged by the seat 6 when 80 in its uppermost position for limiting upward travel of the seat. Filler 8 is threaded into both the bottom of container 1 and into the upper end of casing 7 and forms the connecting means 85 therebetween. The tubular extension 5 is formed with lateral openings 9, 9 adapted, when the extension is in its uppermost position as indicated in dotted lines in Fig. 1, to afford free communication from the 90 container 1 to the interior of the extension 5. Below the seat 6, the casing 7 is preferably provided with an internal annular shoulder 10 adapted to form the limit of downward movement of the seat 6, and 95 the casing extends below the shoulder 10 and is adapted to receive a tube or other suitable connection 11 extending to the cylinder of an internal combustion engine for purposes hereinafter specified.

The valve seat 6 comprises a centrally apertured disk having the extension 5 preferably formed integral therewith, but obviously the said extension may be suitably connected to the disk, the said extension projecting upwardly from the upper face of the disk, and the lower face of the disk being formed with a concavity 12 and with

a transverse groove 13 of slightly greater depth than the concavity. Arranged within the groove 13 is a flap or butterfly valve consisting of a plate 14 of a width substantially equal to the width of the groove 13 and snugly fitting between the walls thereof, the plate being loosely sustained by a supporting bolt 15 which extends through the plate and is threaded into the seat 6, the bolt having a relatively large head disposed beneath the plate. The plate 14 is of a length sufficient to extend from the bolt 15, at one side of the bore of said seat 6, to the opposite side of said bore.

15 While the valve structure thus far set forth is particularly adapted for lubricating systems especially designed for supplying a lubricant to the cylinder of an internal combustion engine, the structure is obviously of general application and the spirit of the invention comprehends the adaptation thereof to the various useful arts, but for purposes of illustration the specific use in conjunction with the operation of an internal combustion engine will be stated. Assuming the parts to be in the position indicated in full lines in Fig. 1 at the time of an explosion within the cylinder with which the tube 11 communicates, the pressure fluid 20 from such explosion ascending the tube 11 and striking the flap valve and seat will close the valve and lift the seat, the extent of upward movement of the seat being, of course, dependent upon the relative amount 25 of pressure, sufficient pressure being required to overcome the weight of the seat, valve and connected parts. As soon as the valve seat and connected parts begin to move upwardly the openings 9 begin to afford 30 communication between the container 1 and the bore of extension 5 and continue to afford such communication so long as the valve seat remains elevated, which of course in the illustrative embodiment under consideration will be as long as the pressure 35 remains in a given cylinder. As soon as the cylinder exhausts, however, the valve seat 6 is free to drop and with the intake for the cylinder the valve seat will be sucked downwardly, the valve 14 being also drawn by the suction to its open position if it has not already fallen by gravity to such position. Thus the charge of lubricant just taken in 40 through the ports or lateral openings 9 is left free to pass the valve 14, flowing across part of the groove 13 and down into the tube 11. It is to be noted here that the provision of the groove 13 enables comparatively sensitive action of the flap valve, the 45 extent of movement of such valve being controlled by the extent to which the bolt 15 is threaded. Furthermore, the concavity in the lower face of the valve seat allows a free 50 passage of the lubricant into the tube 11, and insures the draining of all fluid from

the valve seat even after the valve has been closed. It should be apparent that the bolt 3 is especially adapted for adjustment relative to the extension 5, the extent to which the lower portion of the bolt projects below the tube 2 governing the extent of opening of the ports 9, whereby the quantity of lubricant admitted at each reciprocation of the valve seat may be effectively adjusted.

Having thus described the invention, what is claimed is:

1. In a valve mechanism, the combination, with a casing, of a valve seat movably mounted therein, a tubular extension projecting from the seat and communicating with the bore of the valve seat, the said tubular extension being adapted to be moved with the movement of the valve seat to and from the position communicating with the source of fluid supply, and a valve connected with the valve seat and adapted to be at times seated across the bore of the valve seat.

2. In a valve mechanism, the combination, with a casing, of a valve seat movably mounted therein, a tubular extension projecting from the seat and communicating with the bore of the valve seat, the said tubular extension being adapted to be moved with the movement of the valve seat to and from the position communicating with the source of fluid supply, a flap valve connected with the valve seat and adapted to be at times seated across the bore of the valve seat, and means for varying the extent of communication between the tubular extension and such supply.

3. In a valve mechanism, the combination, with a casing and a fluid supply container disposed above the casing, of a valve seat movably mounted within the casing, a tubular extension projecting from the valve seat upwardly into the container, means for closing the upper end of the tubular extension, the tubular extension being formed with a lateral port and the valve seat being movable to an extent sufficient for causing the port to move at times into position for affording communication between the container and the tubular extension, the bore of the tubular extension communicating with the bore of the valve seat, and a flap valve for controlling the passage of fluid through the bore of the valve seat.

4. In a valve mechanism, the combination, with a casing and a fluid container arranged above the same, of a valve seat movably mounted in the casing and adapted to be moved toward and away from the container, a tubular extension communicating with the bore of the valve seat and extending from the valve seat toward the container, said tubular extension being formed with a lateral port adapted at times to afford communication between the container and the

tubular extension, a tubular member surrounding the upper end portion of the tubular extension, means for adjusting the tubular member relative to said extension for
5 varying the extent of communication through said port, and a valve for the valve seat.

In testimony whereof I affix my signature in presence of two witnesses.

MICHAEL J. KULLA.
